(57) **CLAIM**

We claim the ornamental design for a cleansing station for cleaning rotary atomizers for painting robots, as shown and described.

DESCRIPTION

FIG. 1 is a side view of a cleansing station for cleaning rotary atomizers for painting robots;

FIG. 2 is another side view of the cleansing station;

FIG. 3 is another side view of the cleansing station;

FIG. 4 is another side view of the cleansing station;

FIG. 5 is top view of the cleansing station;

FIG. 6 is a perspective view of the cleansing station; and,

FIG. 7 is a bottom view of the cleansing station.

Portions of the cleansing station shown in broken lines form no part of the claimed invention.

1 Claim, 5 Drawing Sheets
